CLAIM

The ornamental design for a cutting tool, as shown and
described.

DESCRIPTION

FIG. 1 is a front view of a cutting tool in accordance with
the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a forth perspective view thereof;

FIG. 11 is a cross sectional view taken along line 11-11 of
FIG. 1; and,

FIG. 12 shows a cutting tool in an environment of use
thereof.

The broken lines shown in the drawings represent portions
of the cutting tool that form no part of the claimed design.
The dashed-dot-dashed lines indicate a boundary between
the claimed portions and the unclaimed portions of the
design.
